Primary Examiner — Kimberly Barnes*(74) Attorney, Agent, or Firm* — Morgan, Lewis & Bockius LLP**CLAIM**

The ornamental design for a mounting rail node, as shown and described.

DESCRIPTION

FIG. 1 is a rear perspective view of a mounting rail node showing our new design;

FIG. 2 is a left-side elevational view thereof;

FIG. 3 is a right-side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is an enlarged view of a portion of FIG. 1.

The dash-dot-dash broken lines in FIG. 8 illustrate the perimeter of a portion of the mounting rail node that is shown enlarged. The dash-dot-dash broken lines form no part of the claimed design. The other broken lines illustrate structure or features that also form no part of the claimed design.
